PIPE

Robert L. Stern, Brooklyn, N. Y., assignor to
L. & H. Stern, Inc., Brooklyn, N. Y., a corporation of New York.

Application February 16, 1940, Serial No. 319,229

2 Claims. (Cl. 131—212)

This invention relates to smoking pipes and has for one of its objects the provision of a pipe so constructed that the smoke drawn through the stem is caused to move through a tortuous path whereby the moisture, burnt tobacco shreds and impurities are prevented from reaching the mouth of the smoker, and a so called "cool and dry" smoke is attained.

In carrying out the invention, I provide a smoke tube within the pipe shank having a lateral outlet opening communicating with longitudinal passages or flutings in a sleeve that surrounds the stem outlet; said sleeve being open at an end facing the bowl and provided with outer flutings or passages through which the smoke passes to enter the smoke passage in the stem and then to reach the mouth of the smoker.

With this arrangement, the smoke is drawn first in one direction; then it reverses its direction of flow and moves in a direction toward the bowl and then flows again in the first direction and out of the stem and into the mouth of the smoker. Such tortuous movement of the smoke aids in the provision of one or more traps in which moisture, burnt tobacco particles and other impurities may collect and thereby be prevented from entering the mouth of the smoker.

A further object of the invention is to provide a pipe constructed as above described wherein the various co-operating parts are so assembled that they may be very easily dismantled when desired to facilitate a rapid and thorough cleaning of the pipe.

In the accompanying drawing, wherein an embodiment of the invention is shown, Fig. 1 is a side elevation, partly in section, of a pipe constructed in accordance with the invention; Fig. 2 is a sectional view through a portion of the stem; and Fig. 3 is a sectional view on the line 3—3 of Fig. 2, looking in the direction of the arrows.

The pipe is provided with a bowl 1 of conventional form from which extends the integral shank 2. Fitted in the shank 2 and having one of its ends in communication with the bowl, is a tube 3 forming a smoke passage. Said tube is surrounded by a threaded portion 4, which can be integrally formed on the tube or the tube can be inserted within it with a force fit. The threaded portion is tightly fitted in the end of the shank 2.

Near its free end which projects for some distance away from the shank 2, the tube 3 is provided in its wall with an outlet opening 5. This

opening, leading laterally from the smoke passage through the tube 3, is enclosed by a fluted sleeve 6 which fits over a considerable portion of the tube 3. The sleeve 6, because of its fluted shape, is formed with interior longitudinal passages 7 which convey smoke emanating from the outlet opening 5 in a direction toward the threaded portion 4. The fluted sleeve is provided with outer channels or passages 8 which serve to convey the smoke in an opposite direction through the chamber 9 and then into the smoke passage 10 of the stem or bit 11 of the pipe.

The fluted sleeve 6 is held in position on the tube 3 by means of a threaded element or head 12, which threads into and serves as a closure for the free end of the tube 3. Provided on the head 12 is a flange or disk 13 which extends over and closes the ends of the inner passages 7 in the fluted sleeve 6, said sleeve being clamped between the disk 13 and a shoulder 14 provided on the tube 3 near the threaded portion 4. The shoulder 14 is of such size that it does not close the passages 7.

Fitted into the stem or bit 11 is an internally threaded bushing 15 which is received upon the threaded portion 4 to detachably secure the stem or bit 11 to the shank. The chamber 9 in the stem encloses the fluted sleeve 6 and the portion of the tube 3 surrounded by the fluted sleeve.

From the foregoing, the operation of the improved pipe will be readily understood. Smoke drawn through the tube 3 passes out of the outlet opening 5 and into the interior passages 7 of the fluted sleeve 6. The smoke is then drawn in a reverse direction or toward the shoulder 14 where it emanates from the open ends of passages 7 and then moves in a reverse direction through the channels or passages 8, through the chamber 9 and passes therefrom into the smoke passage 10 and into the mouth of the smoker.

By the arrangement of passages described, the smoke moves through a tortuous path so that moisture, burnt tobacco particles, and other impurities are trapped either in the end of the tube 3 or in the chamber 9. The pipe can easily be cleaned of these accumulations since the removal of the threaded element 12 opens up the end of the tube 3, permits removal of the fluted sleeve 6 and uncovers the outlet opening 5 for cleaning.

What I claim is:

1. In a pipe, a bowl, a shank extending therefrom, a tube communicating at one end with the interior of the bowl and having its other end projecting from the end of the shank, said

tube having an integrally formed threaded portion located at the end of the shank, a stem provided with an internally threaded part removably received on the threaded portion of the tube, the tube having a shoulder of less diameter than its threaded portion, said shoulder being located on the tube adjacent to the threaded portion, the tube having an outlet opening in its side wall at a position remote from the shoulder, a fluted sleeve surrounding the tube, said sleeve having one end in abutment with the shoulder but not closed by said shoulder, a threaded element received into the end of the tube adjacent to the outlet opening and closing said end, said threaded element having an annular flange portion abutting against an end of the fluted sleeve to thereby clamp said sleeve between it and the shoulder on the tube and to close both the end of the tube and the end of the sleeve remote from the shoulder, the flutings in said sleeve providing inner passages for the conveyance of smoke toward the bowl and outer passages for the conveyance of smoke toward the stem.

2. In a pipe, a bowl having a shank, a tube leading therefrom, a stem threaded on said tube and enclosing the same, an annular shoulder on the tube adjacent to the connection of said tube with the shank, a fluted sleeve of greater diameter than the shoulder surrounding the tube and having one of its ends clamped against the shoulder by means entrant into the tube and supported thereby, the tube being provided with
- 5 a lateral outlet opening communicating with the interior of the sleeve, said means entering the tube also closing both one end of the tube and the adjacent end of the sleeve, said means holding the opposite end of the sleeve clamped against the shoulder and including a stud adjustably received into one end of the tube, the sleeve having inner passages for conveyance of smoke in a direction toward the bowl and having outer passages for conveyance of smoke toward the stem, the ends of said passages located at the shoulder being open and unobstructed by said shoulder.
